CARRIER-CURRENT PHASE-ANGLE
RELAYING SYSTEM

Herbert W. Lensner, East Orange, and Shirley L. Goldsborough, Basking Ridge, N. J., and Robert C. Cheek, Pittsburgh, Pa., assignors to Westinghouse Electric Corporation, East Pittsburgh, Pa., a corporation of Pennsylvania

Application June 30, 1947, Serial No. 758,200

5 Claims. (Cl. 175—294)

1

Our present invention is an improvement on protective relaying systems of the type in which carrier current is utilized to effect a direct comparison of the phase-angles of the currents at the two ends, or at a plurality of terminals, of the protected line-section of an alternating-current transmission system. More specifically, our invention is an improvement in the type of carrier-current phase-angle relaying system which is shown in the Mehring Patent 2,408,868, granted October 8, 1946, which is characterized by a pair of alternately fired gas-filled tubes, which produce square-topped voltage-waves during alternate half-cycles of the line-current at the relaying station, one of said tubes being utilized to transmit restraining impulses to the opposite end of the protected line-section, by the aid of carrier, and the other gas-tube being utilized to apply operating impulses to the phase-angle-responsive relay. The Mehring system utilized a single fault-detector for setting the carrier-controlling gas-tube into operation, and the other gas-tube was biased so that it would not respond quite as sensitively as the fault-detector, in response to fault-currents.

The Mehring patent also utilized a line-current-responsive network for deriving a single-phase alternating-current quantity which is responsive to a plurality of different line-fault conditions, on a 3-phase line, as broadly covered by the Harder Patent 2,183,646, granted December 19, 1939. The Mehring patent was a more direct outgrowth of a phase-angle-responsive relaying system of the type shown in the Bostwick Patent 2,275,941, granted March 10, 1942, which effected a phase-angle comparison without utilizing a pair of alternately triggered gas-tubes for producing the two series of constant-magnitude, square-topped voltage-impulses, on alternate line-current half-cycles, for respectively producing the operating and restraining impulses. The Bostwick system utilized two fault-detectors of differing sensitivities; the more sensitive, or low-set, fault-detector being utilized to supervise the transmission of carrier on alternate line-current half-cycles, while the less sensitive, or high-set, fault-detector was utilized to supervise the phase-angle relay. The Bostwick system required carrier-current of a different frequency for each line-terminal, and it also involved a difficult problem of correlating the settings of a plurality of different kinds of current-responsive and current-limiting devices.

Our present invention is more particularly related to the Mehring system, which was one of

the most successful forms of phase-angle-responsive carrier-current relaying, prior to our invention. The outstanding feature which contributed most largely to the success of the Mehring system was the use of the two alternately firing gas-tubes which were controlled by a derived single-phase current which was responsive to all kinds of faults, on any of the phases of a 3-phase transmission-system. We avoid, however, two disadvantages of the Mehring system which, for a while, could not be avoided, for lack of any obvious way to do so, without sacrificing the one most important or essential feature which has just been described.

15 In the Mehring system, it was necessary to bias the second gas-tube, so that its firing-point would be higher than, say 125% of the pick-up value of the fault-detector. This had the disadvantage of sometimes transmitting carrier continuously, as a result of the firing of the first gas-tube, under fault-conditions which were not sufficiently severe to initiate the firing of the second gas-tube on alternate half-cycles of the line-current, thus producing a "blind-spot" in 20 the relay, which not only prevented the tripping of the relay at the terminal where such a condition arose, but also, because of the continuous transmission of a carrier-signal, which was utilized for blocking, preventing a relay-operation at any other terminal of the line-section in question. It also posed a difficult problem of maintaining the proper correlation between the pick-up value of a mechanical relay, which is affected only by the severity of the derived line-current, 25 and the pick-up value of a gas-tube, which is dependent also upon any variation in the direct-current supply-voltage for the tube. The quicker action of the tube also involved a difficulty, in correlating the pick-up value of the second gas-tube with the pick-up value of the mechanical fault-detector relay in the Mehring system, because of the sensitivity of the tube to very-short-duration transients in either the alternating-current source or the direct-current system to 30 which the tube is connected.

An object of our invention is to provide a system of the general class described, in which it is impossible to continuously transmit carrier current in response to a fault.

35 50 A further object of our invention is to provide a system of the class described, in which no dependence is placed upon the firing-point of one of the alternately triggering gas-tubes, for the trip-setting.

55 A more specific object of our invention is to

provide a relay system in which the firing-points of both of the gas-tubes are lower than the pick-up value of a first mechanical fault-detector relay, which has a low setting, while using a second mechanical fault-detector relay, having a higher setting, to prevent the effective operation of the phase-angle relay unless this second fault-detector relay also responds. This correlation is needed, in order to make sure that a succession of restraining impulses shall always be applied to the relay, before, or at least simultaneously with, the application of a succession of operating-impulses to the relay.

With the foregoing and other objects in view, our invention consists in the systems, circuits, combinations, elements and methods of design and operation, which are hereinafter described and claimed, and illustrated in the accompanying drawing, the single figure of which is a much simplified diagrammatic view of circuits and apparatus illustrative of our invention in a preferred form of embodiment.

In the drawing, we have illustrated our invention as applied to one terminal of a line-section 1 of a 3-phase transmission-line, which is connected to a 3-phase station-bus 2 by means of a circuit-breaker 3 having a trip-coil TC and an auxiliary make-contact 3a. We have shown only one terminal of the protected line-section 1, with the understanding that the other terminal is, or may be, a duplicate of the terminal equipment which is illustrated.

We utilize a bank of line-current transformers 4, which respond to the 3-phase line-current in the protected line-section 1, and supply this current to any suitable network or filter, which is marked HCB, for deriving a single-phase alternating-current voltage which is applied to the primary winding of a saturable transformer ST. Any suitable network, such as HCB, may be utilized, for deriving a single-phase relaying current or voltage which is reasonably uniformly responsive to a plurality of kinds and severities of faults on whatever line-phase a fault may occur. The secondary winding 6 of the saturable transformer ST is shunted by a voltage-limiting gas-filled tube GT-1, as described in the Harder patent.

The secondary winding 6 is utilized to control two mechanical fault-detector relays FD1 and FD2 having diverse sensitivity-settings, and also to control two alternately triggering gas-filled tubes V1 and V2. The operating-coils of the two fault-detector relays FD1 and FD2 are shown as being energized in series with each other, from the output-terminals of a rectifier-bridge RB, which is supplied with energy from the secondary winding 6 of the saturating transformer ST. The gas-filled tubes V1 and V2 are controlled from the aforesaid secondary winding 6 by having the tube-grids G1 and G2 energized, through resistors R1 and R2, from two secondary windings 11 and 12 of an input-transformer IT, the primary of which is energized from the secondary winding 6 of the saturated transformer ST. The other two terminals of the secondary windings 11 and 12 of the input-transformer IT are shown as being connected together, in a circuit 14 which is connected to an intermediate tapped-point of a cathode-circuit biasing-resistor R3, which is in the cathode-circuits of the gas-tubes V1 and V2.

As shown in the drawing, one terminal of the cathode-circuit biasing-resistor R3 is connected to the negative bus (—) of a direct-current voltage-source for the tubes, while the other termi-

nal of said resistor is connected to a conductor 15, which is utilized for several purposes. The circuit 15 is utilized to energize one terminal of a cathode-circuit loading-resistor R4, the other terminal of which is connected to the cathode-terminal 21 of the first gas-tube V1. The circuit 15 is also utilized to energize one terminal of another cathode-circuit loading-resistor R5, the other terminal of which is connected to the cathode-circuit 22 of the second gas-tube V2.

The two grid-terminals of these tubes V1 and V2 are connected to their respective cathode-circuits 21 and 22 through capacitors C1 and C2, as is known in the art. The two plate-circuits 15 P1 and P2 of these two tubes are connected together through a capacitor C3 which assists in the firing-transfer, as explained in the Mehring patent. The two cathode-circuit loading-resistors R4 and R5 are respectively shunted by capacitors C4 and C5, which also assist in the firing-transfer, as set forth in the Mehring patent. The circuit 14, which is connected to an intermediate tap of the cathode-circuit biasing-resistor R3, is also connected to the circuits of the screen grids SG1 and SG2 of the respective gas-tubes V1 and V2. The two plate or anode-circuits P1 and P2 of the two gas-tubes are connected, respectively, through resistors R6 and R7, to a common conductor 24, which is in turn connected to the positive bus (+) through a resistor R8.

The two alternately firing gas-tubes V1 and V2 are supervised by the low-set fault-detector FD1, by having the positive tube-circuit 24 connected to the negative terminal (—) through the normally closed back-contact 25 of the low-set fault-detector FD1.

The circuits of the several relays which are utilized in our invention are arranged, as far as practicable, after the manner of a schematic diagram or "across-the-line" diagram. In each case, the main or operating coil of the relay is given a letter-designation or legend, and the same letter-designation or legend is applied to all of the contacts of that relay. The relays and switches are invariably shown in their open or deenergized positions. Arrows or dotted lines are used, to symbolically indicate how the various parts of each relay are connected together.

The back-contact 25 of the low-set fault-detector FD1 is also utilized to control the energization of an auxiliary relay K, by having the operating-coil K of this auxiliary relay connected, through a resistor R9, across the FD1 back-contact. The auxiliary relay K has a single back-contact K, which is connected in series with a telemetering key TM, which is indicated by way of illustration of carrier-current control for purposes other than relaying. The auxiliary-relay back-contact K thus acts substantially like a back-contact placed upon the low-set fault-detector FD1, said auxiliary relay K being utilized for supplying this contact in order to avoid overloading the low-energy fault-detector FD1.

The cathode-circuits 21 and 22 of the respective gas-filled tubes V1 and V2 are utilized as sources of two alternating series of square-topped positive-voltage impulses, for two different purposes. These positive-voltage impulses are the voltage-drops through the respective cathode-circuit loading-resistors R4 and R5, which have voltage-drops therein when their respective tubes V1 and V2 are firing.

The cathode-circuit 21 of the first gas tube V1 is utilized to energize the plate-circuit P3 of a

carrier-current master-oscillator tube OSC, through a radio-frequency choke-coil RFC-1. During fault-free conditions of the transmission system, the gas-tubes V1 and V2 are not firing, because of the short-circuiting back-contact FD1, and at such times the carrier-current oscillator OSC may be energized through the telemetering key TM, and the back-contact K, which connect the circuit 21 to the positive bus (+) through a resistor R-10.

The transmitter-oscillator OSC has its screen-grid SG3 connected to the plate-supply circuit 21 of said oscillator. The cathode-circuit of the oscillator OSC is the previously-mentioned circuit or conductor 15. The oscillator has a grid-circuit G3, which is connected to the cathode-circuit 15 through a grid-resistor R-11.

The plate-circuit P3 of the oscillator OSC is connected, through a blocking-capacitor BC1, to an intermediate terminal 27 of a tuned carrier-frequency circuit, comprising the conductor 27, a capacitor C6, a conductor 28, a capacitor C7, the cathode-circuit 15, a capacitor C8, the grid-circuit G3, and a variometer L1, the other terminal of which is connected to the starting-point 27 of the tuned circuit.

The conductors 28 and G3 of this tuned circuit are respectively utilized to apply radio- or carrier-frequency control-voltages, through blocking-capacitors BC2 and BC3 respectively, to the grids of two amplifier-tubes A1 and A2. The cathodes of the amplifiers A1 and A2 are connected to the cathode-circuit 15 of the oscillator OSC. The grids of the amplifier tubes A1 and A2 are connected, through grid-resistors GR1 and GR2, to the negative bus (-), so as to apply a negative bias equal to the drop across the cathode-circuit biasing-resistor R3. The two plates of the amplifiers A1 and A2 are connected to the primary-winding terminals of a radio-frequency output-transformer OT. The primary winding of said output-transformer OT has a midpoint tap 30 which is connected to the positive supply-terminal (+) and also to the screen-grids of the two amplifiers A1 and A2.

The radio-frequency output-transformer OT has a secondary winding 31, having one of its terminals grounded, and having two taps 32 and 33. The output-transformer secondary-tap 32 is connected to phase-C of the line 1, through a variometer L2, a conductor 34, and a coupler-capacitor CC. The conductor 34 is also grounded through a grounding-coil GC. The secondary tap 33 of the radio-frequency output-transformer OT is utilized to energize the primary winding of a receiver-coupling transformer RCT, through a tuning-capacitor T-C. The primary winding of the receiver-coupling transformer RCT is also preferably protected by a shunt-connected voltage-limiting gas-filled tube GT-2.

The receiver-coupling transformer RCT has a secondary winding 36 which is part of a tuned receiving-circuit, comprising said secondary winding 36, the grid-conductor G4 of a receiver-tube REC, a tuning-capacitor C9, the circuit or conductor 15 and thence back to the secondary winding 36.

The receiver-tube REC is a saturating-tube which carries a plate-cathode current which is of a substantially constant magnitude, whenever the tube is conducting at all, substantially regardless of the voltage applied to the grid-circuit G4, provided that this grid-voltage is high enough to cause plate-current to flow.

The receiver-tube REC has its cathode-circuit

37 energized from a tapped point of a potentiometer PO4 which is connected between the circuit 15 and the positive bus (+). The receiver-tube REC has a plate circuit P4, which is energized from the positive supply-terminal (+) through a radio-frequency choke-coil RFC-2. In the drawing illustrative of our invention, we have symbolically shown the telemetering relays 38 in series with the plate-circuit P4, although it should be understood that, in general, the telemetering relays 38 would be utilized only at one line-terminal, while the telemetering key TM would be utilized at the other line-terminal. The receiver-tube REC also has a screen-grid circuit SG4 which is connected to the positive terminal (+).

The receiver-tube plate-circuit P4 is utilized to apply a restraining voltage to the grid-circuit G5 of a relay-tube RT, through a coupling-capacitor C-10, a conductor 39, a voltage-doubler which is generically indicated at 40, and a grid-circuit resistor R-12. The voltage-doubler, as explained in the Mehring patent, consists of a resistor R-13, which is connected between the conductor 39 and the cathode-circuit 22 of the second gas tube V2, a capacitor C11, which is connected between the circuit 39 and a circuit 41, a double-circuit rectifier-valve RV, and a loading-resistor R-14. The loading-resistor R-14 is connected between the cathode-circuit 22 of the gas tube V2 and the anode circuit 42 of the right-hand rectifier of the rectifier-valve RV. The circuit 42 also constitutes one terminal of the grid-circuit resistor R-12 of the receiver-tube RT. The cathode of the right-hand half of the double-rectifier valve RV is connected to the conductor 41, while the anode of the left-hand rectifier-circuit of the doubler valve RV is connected to the same conductor. The cathode of the left-hand rectifier of the double valve RV is connected, at 43, to the cathode-circuit 22 of the second gas valve V2. The loading-resistor R-14 is by-passed by a radio-frequency by-pass capacitor EPC.

The relay-tube RT has its cathode-circuit 44 energized from a tapped point of a potentiometer PO5 which is connected between the conductor 15 and the positive supply-terminal (+). The plate-circuit P5 of the relay-tube RT is connected through the primary winding of a relay output-transformer ROT, a conductor 45, a make-contact 46 of the high-set fault-detector FD2, and thence to the positive terminal (+). The screen-grid circuit SG5 of the relay-tube RT is also connected to the aforesaid conductor 45.

The relay output-transformer ROT has a secondary winding 47, which is utilized to energize the operating coil R of a relay R which has a single make-contact 48, which is shown, near the top of the negative supply-terminal (-), as being in the tripping-circuit of the trip-coil TC of the circuit breaker 3, this trip-circuit extending from the negative bus (-) to the positive bus (+), and also including the auxiliary breaker-contact 3a.

In describing the operation of our invention, we will pay particular attention to the distinguishing features which distinguish the invention from the system which has already been described and claimed in the previously-mentioned Mehring Patent 2,408,868. When a fault of a predetermined severity occurs on the protected line-section 1, one or both of the two fault-detectors FD1 and FD2 will pick up. The low-set detector FD1 is the more sensitive of the two, and when

it responds, it opens its back-contact 25, and thus removes a short-circuit from around the two gas tubes V1 and V2. The grid-circuit settings of both of these gas-tubes V1 and V2 are more sensitive than the sensitive fault-detector FD1, so that said tubes are already in readiness to fire, in response to the alternating voltages which are applied to their respective grids G1 and G2, as soon as the sensitive fault-detector FD1 responds.

Whichever one of the two gas tubes V1 and V2 has a positive grid voltage applied to it, at the moment of opening of the FD1 back-contact 25, will instantly begin firing, developing a certain positive voltage in its cathode-circuit 21 or 22, as the case may be, making said cathode-circuit positive with respect to the conductor 15. During the next half-cycle of the line-current, or output of the secondary winding 6 of the saturating transformer ST, a positive grid-voltage is applied to the other one of the two gas-tubes V1 and V2, causing this other tube to fire, putting out the first-firing gas-tube, in the process, as explained in the Mehring patent. This process is called "triggering" the two gas-tubes V1 and V2. It will be understood, of course, that these two triggering tubes V1 and V2, since they are gas-tubes, are sustained-discharge tubes, that is, tubes in which the grid fires the tube, or starts the discharge, but is unable to extinguish the tube or interrupt the discharge, as explained in the Mehring patent. The two gas-tubes V1 and V2 thus operate as sources of two different series of flat-topped voltage-waves of constant magnitude, one gas tube being responsive to positive line-frequency half-cycles, while the other is responsive to negative line-frequency half-cycles.

Carrier-current is transmitted by the firing of the master-oscillator tube OSC during the flat-topped voltage impulses which are supplied from the cathode-circuit 21 of the first gas-tube V1, thus transmitting a succession of bursts of carrier-current energy, which are applied to the line through the coupling capacitors CC, during line-current half-cycles of one polarity. During the line-current half-cycles of the other polarity, positive or operating-voltage is applied to the grid-circuit G5 of the relay-tube RT through the cathode-circuit 22 of the second gas-tube V2, the voltage of the circuit 22 being applied to the grid-circuit G5 through the resistor R-14, the conductor 42, and the resistor R-12. This operating-voltage tends to cause the flow of plate-current in the relay-tube RT.

As explained in the Mehring patent, the carrier-current impulses which are transmitted from both ends of the protected line-section are received in the receiver-tube REC at each end of the line-section, but the only important received carrier-impulses, at either end, are those which are received from the far end of the protected line-section, because the carrier-current impulses, or bursts, or operating-periods, which are transmitted from the relaying station itself, always occur during the half-cycles of the line-current when no operating-voltage is applied to the grid-circuit G5 of the relay-tube RT from the cathode-circuit 22 of the second gas tube V2. At the far end of the protected line-section, however, the carrier-current energy-impulses or bursts, which are transmitted at line-frequency half-cycle intervals, are transmitted in response to the cathode-circuit 21 of the first gas tube V1 in that station, so that, if the line-current at the far-end station is in phase with the line-current at the relaying station (as it will be, when there

is no fault in the protected line section), then the carrier-current transmitting-periods at the far end will exactly coincide with the operating-voltage half-cycle periods at the relaying station, 5 and thus they will block a response of the relay-tube RT.

The received carrier-current energy is applied, in a blocking fashion, to the grid-circuit G5 of the relay-tube RT, through the coupling capacitor C-16 and the voltage-doubler 30, which operates as described in the Mehring patent, so as to build up a negative voltage, in the loading resistor R-14, which is at least as large as, and opposite in sign to, the positive grid-voltage which is supplied by the cathode-circuit 22 of the second gas tube V2.

The result of the foregoing operations is that the relay-tube RT will become conducting only when there is an internal fault, or a fault within 10 the protected line-section 1, in which case the tube will become conducting periodically, in short or long bursts, depending upon the phase-relations between the line-currents at the opposite ends of the protected line-section. The alternating-current component of the plate-current of the relay-tube RT is applied to the operating coil of the phase-angle-responsive relay R, through the relay output-transformer ROT. The contact 48 of the relay R is then utilized to trip the 15 breaker 3.

It will be noted that the carrier-current equipment acts as a pilot-channel connecting the two ends of the protected line-section for the purpose of effecting a determination or comparison of 20 the phase-angle between the two terminal line-currents of the protected line-section.

In order to insure the proper operation of the relay R, in view of its dependence upon fault-responsive relay-operations at two widely-separated points, namely at the two opposite ends of the protected line-section, it is necessary to make 25 sure that the restraining impulses which are applied to the relay-tube RT are applied at least as soon as, and usually a trifle ahead of, the effective application of the operating-impulses to the grid-circuit G5 of this relay tube RT.

In the Mehring system, this coordination was obtained by biasing the second gas-tube V2 so that it would have a pick-up value some 25% higher than the fault-current magnitude which 30 resulted in a picking up of the single fault-detector relay which was utilized in said Mehring system, thereby entailing difficulties due to the impossibility of properly coordinating the gas-tube pick-up value with the mechanical-relay pick-up value, because of the dependence of the tube-operation on the station battery-voltage represented by the terminals (+) and (-), and also because of the much more sensitive responsiveness of the tube to short-term transients on 35 both the alternating-current control-voltage of the tube, and the direct-current plate-voltage source for the tube. Even aside from these coordination problems, the Mehring system was subject to the possibility of a "blind spot" in its operation, in the event of a fault which was barely severe enough to pick up the mechanical fault-detector, but not severe enough to fire the second gas tube V2, and also in the case in which the 40 fault-currents, which were fed into a fault from the opposite ends of the protected line-section, were unequal in value, so that the second gas tube at the end having the smaller current would not fire, resulting in a continuous or uninterrupted transmission of carrier, which would block 45

a tripping-action at both ends of the protected line-section.

In accordance with our invention, we avoid these coordination-defects and "blind-spot" contingencies by having both of the gas-tubes **V1** and **V2** operative, or in condition for firing, at the lowest fault-current value which will result in a picking up of the low-set or sensitive fault-detector **FD1**. Thus, when carrier is transmitted at all, it is always transmitted on alternate half-cycles of the line-current at the station where the carrier is being transmitted. In accordance with our invention, we secure the less-sensitive fault-detection coordination, by utilizing a second mechanical fault-detector relay **FD2**, which responds to the same derived fault-current which is utilized to energize the first fault-detector relay **FD1**, but which has a slightly higher setting, such as responding to a current-value of approximately 125% of the pick up of the first fault-detector **FD1**.

In accordance with our invention, we also make use of a back-contact, 25 (rather than a make-contact), on the first fault-detector **FD1**, because a back-contact will not bounce, in response to a fault, thus avoiding the possibility of a momentary interruption of the transmission of a blocking or restraining signal at the beginning of a fault, thus resulting in false tripping at the opposite terminal. We also use a make-contact, 46, on the second fault-detector **FD2**, so that, even though both of the fault-detectors should pick up simultaneously, the detector having the back-contact will get that contact open before the other detector has moved far enough to close a normally open make-contact, thus insuring that a restraining-voltage is available, on the relay-tube **RT**, a trifle ahead of the effective application of an operating-voltage to the relay tube **RT**. It will be understood, of course, that the blocking of the operating voltage of the tube can be effected either by preventing the application of a sufficiently positive grid-voltage to the tube, or by preventing the application of a sufficient plate-voltage to the tube. In the illustrated case, the blocking of the operating voltage is effected by preventing the application of a plate-voltage to the tube.

It will be noted, finally, that we avoid shock-excitation defects, due to responses to transients, by utilizing the same kind of mechanical relays for both of our fault-detectors **FD1** and **FD2**, so that our phase-angle relaying-system operates satisfactorily, without any of the disadvantages inherent in the Mehring system.

We claim as our invention:

1. Terminal equipment for one terminal of a pilot-channel phase-angle relaying-system for an alternating-current transmission-line, comprising the combination, with a relay to be controlled, and a pilot-channel means for communicating with another terminal of the protected line-section, of means for deriving an alternating-current line-current relaying quantity which is responsive to a plurality of different line-fault conditions, two line-current-responsive fault-detector means of differing sensitivities, line-current-responsive impulse-producing means, operating under the supervision of the low-set fault-detector means, for applying a succession of operating-impulses, effective on said relay, in response to derived line-current half-cycles of one polarity, and for delivering a succession of pilot-channel-controlling impulses to said pilot-channel means in response to derived line-current im-

pulses of the opposite polarity, receiving-means for applying restraining-impulses, effective on said relay, in response to pilot-channel impulses received from another terminal of the protected line-section, and means for supervising said relay in response to the high-set fault-detector means.

2. Terminal equipment for one terminal of a pilot-channel phase-angle relaying-system for an alternating-current transmission-line, comprising the combination, with a relay to be controlled, and a pilot-channel means for communicating with another terminal of the protected line-section, of two line-current-responsive fault-detector means of differing sensitivities, line-current-responsive impulse-producing means, operating under the supervision of the low-set fault-detector means, for applying a succession of operating-impulses, effective on said relay, in response to derived line-current half-cycles of one polarity, and for delivering a succession of pilot-channel-controlling impulses to said pilot-channel means in response to derived line-current impulses of the opposite polarity, receiving-means for applying restraining-impulses, effective on said relay, in response to pilot-channel impulses received from another terminal of the protected line-section, and means for supervising said relay in response to the high-set fault-detector means, 20 said operating-impulses, said pilot-channel-controlling impulses, and said restraining-impulses all being substantially flat-topped impulses of substantially constant magnitudes which are substantially independent of the fault-severity, the magnitude of the derived line-current, or the magnitude of the received energy which is received over said pilot channel.

3. The invention as defined in claim 1, characterized by the two fault-detector means being similarly operating, and similarly energized, equipments having different settings, both controlled in response to the same derived line-current which is used in said impulse-producing means.

4. The invention as defined in claim 1, characterized by the two fault-detector means being similarly operating, and similarly energized, mechanical relays having different settings, both controlled in response to the same derived line-current which is used in said impulse-producing means, the low-set fault-detector relay having a normally closed contact, which opens when the relay responds to a fault, and the high-set fault-detector relay having a normally open contact, which closes when the relay responds to a fault, the fault-detector supervision which is specified in claim 1 being effected by said contacts, respectively.

5. The invention as defined in claim 1, characterized by said impulse-producing means comprising two gas tubes of the sustained-discharge type, each tube having trigger-acting control-circuit means for firing the tube, direct-current plate-cathode-circuit energization - means for said two gas tubes, interconnecting impulsing-means between the plate-cathode circuits of said two gas tubes for responding to the moment of firing of either tube in such manner as to so impinge the effective plate-cathode voltage across the other tube as to extinguish said other tube, means for so applying said relaying quantity to the control-circuit means of the two gas tubes that the tubes fire during half-cycles of opposite polarity of said relaying quantity, the grid-cir-

cuit settings of both of said gas tubes being more sensitive than the sensitive fault-detector, means responsive to the discharge of one of said gas tubes for delivering a pilot-channel-controlling impulse to said pilot-channel means as long as said discharge lasts, and means responsive to the discharge of the other gas tube for applying an operating-impulse, effective on the relay, as long as said discharge lasts.
